UNITED STATES PATENT OFFICE.

EDWARD JOSEPH MAHER, OF JERSEY CITY, NEW JERSEY.

SKIRT-SUPPORTER.

1,304,340.

Specification of Letters Patent. Patented May 20, 1919.

Application filed July 16, 1918. Serial No. 245,160.

To all whom it may concern:

Be it known that I, EDWARD JOSEPH MAHER, citizen of the United States, and resident of Jersey City, in the county of 5 Hudson and State of New Jersey, have invented certain new and useful Improvements in Skirt-Supporters, of which the following is a specification.

My invention relates to a belt or girdle; 10 especially a girdle designed to fit around a human body and support a garment thereon.

An object of my invention is to provide a girdle adapted particularly for feminine 15 use and so made that it can always encircle the owner's waist in substantially one and the same position and yet be capable of holding the garment that it supports, for example, the dress skirt, at a predetermined 20 height, and for adjusting the height at pleasure, according to the length of the skirt, *i. e.* the position of the skirt band, due to the changing fashion of wearing the apparel referred to.

25 The drawings and description disclose the best embodiment of my invention now known to me, but I reserve the right to make changes in what is actually shown herein to the full extent indicated by the general 30 meanings of the terms employed in the appended claims.

On the drawings:

Figure 1 is a front view showing a girdle made according to my invention as it would 35 appear on the wearer, the garment partially attached thereto.

Fig. 2 is a plan view of such a girdle extended; and

Fig. 3 is an enlarged sectional view taken 40 on the line 3—3 of Fig. 1.

I show at 1 a band to encircle the wearer's waist, and above the band 1 is a similar band 2 to be substantially parallel with the band 1. The upper and lower bands of the girdle 45 can be made out of any suitable material, such as canvas tape or other stout cloth, and they are united by connecting and supporting members 3, which hold the two bands together and carry the band 2 above the 50 band 1 when the girdle is placed about the waist line of the wearer's body. Each member 3 is adjustable as to length so that the distance between the two bands can be varied. Hence the band 1 can be applied to the 55 wearer's waist always in one and the same position; while the skirt or other garment

4 can be worn in different positions simply by altering the location of the band 2, relative to the band 1. In other words, when the skirt is attached to the band 2 it can 60 be worn higher or lower according to the length of the members 3; and by adjusting the lengths of the members 3 before the skirt is put on, the desired effect can in every case be easily and quickly obtained, to which 65 is added the advantage of retaining the skirt definitely in the intended position.

To attach the skirt to the girdle I provide the upper band 2 with fastening devices 5 and the skirt is joined to a band 6, having 70 fastening devices 7. Any suitable form of fastening devices may be employed, but I prefer the well known glove fastener; making the devices 5 serve as the male elements and the devices 7 as the female elements 75 thereof, so that when the skirt 4 and band 6 are secured together, and the elements 7 are caused to receive the elements 5 in engagement, the skirt will be held up by the 80 girdle as required.

To secure the skirt to the band 6, the band 6 may be sewed or otherwise attached with whatever degree of permanency desired; but in the present form I employ metal staples or fasteners 8 carried by the band 6, the 85 points of the staples 8 being passed through the usual band inside the skirt 4 and then bent down to keep from releasing the skirt as will be understood.

Each member or upright or brace 3 is 90 made adjustable to vary its length and in the form illustrated this adjustable feature is provided by constructing it in two parts; one part such as the lower portion indicated at 9 having a slot 10 and the upper part 11 carrying an element 12 to engage the slot 10. The element 12 in each case may be a rivet fast to the part 11 passing through the slot 10 and having a head on one end and its opposite end flattened to retain a washer 100 on it, and against the edges of the slot 10. A similar washer may be placed on the rivet 12 between the parts 9 and 11 if desired, so that the parts 9 and 11 may be rendered 105 more readily adjustable without binding upon each other when moved.

The parts 9 and 11 of each member 3 will also carry fastening devices to hold them in their proper relative positions. At the upper end of each lower part 9 will be a 110 male fastening element 13, similar to the elements 5, and in each upper part 11 above

the rivet 12 will be several female fastening elements 14 similar to the elements 7. By disengaging the parts 9 and 11, and manipulating them to attain the right length, 5 they can be secured by snapping the elements 13 into the elements 14. When the elements 13 and 14 are thus engaged they coöperate with the element 12 in holding the parts 9 and 11 of each member in alinement.

In practice the girdle is put on by placing the band 1 around the waist and securing its ends together by a buckle 15 or any convenient fastening means, the band 2 having 15 its ends united by similar means. The members 3 being adjusted to the length desired, the wearer can don the skirt by forcing the elements 5 of the band 2 of the girdle into the elements 7 of the band 6 attached to the 20 skirt. Hence the skirt 4 can be worn higher or lower according to the wearer's wish, or as the length of the garment or as the prevailing style of wearing the skirt band may suggest.

25 The girdle is quite simple, comprises but few parts, and costs but little to produce. It can be worn by any one and on account of the ease with which it can be manipulated, it is unlikely to get out of order or become 30 damaged from use.

When the girdle is put on, the skirt waist above the skirt may be inside the band 2 or over it if desired. To enable the band 6 for the skirt to be joined to the latter, the 35 skirt may have an inside or lining to be engaged by the fasteners 8; whereby the fasteners will not be visible on the outside of the skirt 4:

While I have thus shown with full details 40 the adjustable means for elevating the band of the skirt at different heights, it is obvious that the belt performs its paramount function in effectually retaining the skirt in the position predetermined upon by the 45 wearer, irrespective of and uninfluenced by the conformation of the waist line, and hence the specific means for effecting said adjustments while in one sense they may be found convenient and highly essential for 50 such universal adaptability, yet it is not my desire to have the other and really more important functions omitted from the scope and operation of the patent therefor. In other words, my invention may be embodied 55 in a girdle with or without the adjustable features described, and which therefore supports a skirt, dress or gown in a relatively secure position above the waist line of the wearer.

60 I am furthermore aware that belts of many kinds have been designed for a variety of uses, and that some have been constructed with more than one encircling member having connecting stays from one to the other, 65 in the broad general manner of my present

disclosure. These plural members however have not prior to my improvement been employed for the specific object of enabling the wearer of a dress skirt to support that article upon the body with the precision of 70 adjustment that will be provided by the device disclosed herein.

I therefore do not claim broadly the structure of a double belt *per se*, but rather such a device that will admit of that predetermined adjustment of the wearing apparel that marks the well dressed person, and to this end it is pointed out that the upper belt, *i. e.*, the one supported upon the uprights 3, may be dispensed with, in which 75 case the upper ends of the uprights would be attached directly to the band 6; or it may be desired to attach the element 7 to the inner face of the skirt band in the first instance, placing the member 5 upon the top 80 end of upright in either of the two methods described above for attaching the skirt to my device.

Having described my invention, what I claim as new and desire to secure and protect by Letters Patent is:

1. The combination with a garment, of an attaching band secured to the garment and a girdle including connected upper and lower bands, the lower one of which is 95 adapted to encircle the waist of the wearer and the upper band being provided with means for detachable engagement with said attaching band, whereby the garment may be suspended from the girdle at a point 100 above the waist line of the wearer.

2. The combination with a garment having a band, of an attaching band secured to the garment band, a girdle including spaced upper and lower bands, the lower one of 105 which is adapted to encircle the waist of the wearer, stays connecting said bands, and interengaging fastening devices carried by the attaching band and upper band for suspending the garment from the girdle at a 110 point above the waist line of the wearer.

3. The combination with a garment having a band, of an attaching band secured to the garment band, a girdle including upper and lower bands, each provided with interengaging ends, the lower band being adapted to encircle the waist of the wearer, interengaging fastening devices carried by the upper band and the attaching band for suspending the garment from said upper band, 120 and vertically adjustable stay members forming a connection between the bands whereby the garment may be suspended from the girdle at different heights above the waist line of the wearer.

4. A garment supporter including a band for attachment to a skirt, a girdle comprising upper and lower bands, the lower one of which is adapted to encircle the waist of the wearer, stay members connecting said 130

bands for supporting the upper band in position above the waist line of the wearer, and interengaging fastening devices carried by the attaching band and upper band of the 5 girdle for suspending the skirt from the girdle at a point above the waist line of the wearer.

5. A garment supporter including a band for attachment to a skirt, a girdle comprising upper and lower bands, the lower one of 10 which is adapted to encircle the waist of the wearer, stays connecting said bands and each formed of mating sections adjustable vertically with respect to each other, one of

the sections of each stay being provided 15 with a slot and the other with a pin extending through said slot, interengaging fastening devices carried by the sections of the stays for securing the stays in different positions of vertical adjustment, and inter- 20 engaging fastening devices carried by the attaching band and upper band of the girdle for suspending a skirt from the girdle at a point above the waist line of the wearer.

Signed at New York, in the county of 25 New York and State of New York, this 10th day of July, A. D. 1918.

EDWARD JOSEPH MAHER.
